No. 874,337.

PATENTED DEC. 17, 1907.

S. W. HELM,

BOX.

APPLICATION FILED MAR. 24, 1906.

UNITED STATES PATENT OFFICE.

SAMUEL W. HELM, OF NEW YORK, N. Y.

BOX.

No. 874,837.

Specification of Letters Patent.

Patented Dec. 17, 1907.

Application filed March 24, 1906. Serial No. 307,830.

To all whom it may concern:

Be it known that I, SAMUEL W. HELM, a citizen of the United States, residing at New York city, in the county of New York and State of New York, have invented new and useful Improvements in Boxes, of which the following is a specification.

My invention relates to improvements in boxes, chiefly, but no exclusively, intended for containing tobacco; and has for its object the provision of such a box which may be, with great facility, slipped into a garment pocket and rest comfortably against the body of the person, and at the same time have an increased capacity for containing tobacco or other articles as compared with boxes heretofore designed for the purposes above indicated.

The invention has for its further object to provide boxes having the features described and, in combination therewith, a lid and means for movably or hinged connecting the same to the box body in such manner that it may be easily and accurately opened and closed.

Having the foregoing objects in view the invention consists in a box possessing the features hereinafter described, and illustrated in the accompanying drawings.

That which is regarded as new will be set forth in the claims appended to the description.

In the accompanying drawings—Figure 1 is a perspective view of the box, the lid being closed; Fig. 2 is a longitudinal sectional view on a line taken through the end walls; Fig. 3 is a sectional view on a line taken through the front and rear walls; Fig. 4 is a horizontal section.

In the said drawings the reference numeral 1 designates, generally, the body of the box, which is relatively deep from the top to the bottom thereof,—the depth may be increased or decreased as may be desired, according to the contemplated capacity of the box. The front wall 2 of the box is concavo-convex, and the ends 3 of the box are also concavo-convex, and merge into the front and rear walls, as will clearly appear from Figs. 1 and 4, without presenting sharp angles, whereby the box may with great facility be introduced into and withdrawn from a garment pocket, such as the side pocket of a coat or the rear pocket of trousers. The rear wall 4 of the box is flat, or, in other words, constitutes a plane surface

which rests easily and comfortably against the body of the person. The provision of the flat or plane rear wall of the box, in addition to other purposes which will be stated, accomplishes the object of imparting within the space practically occupied by the box, an increased holding capacity, as compared with prior boxes in which one wall of the box is convex and the other concave.

As shown the front and end walls of the box are folded inwardly to constitute strengthening ribs 5, 5^a for the upper and lower edges of the box body and the lower edge of the rear wall is correspondingly folded inwardly to constitute a rib 6, which, together with the rib 5^a at the bottom of the front and end walls constitute a supporting flange for the bottom 7 of the box, which may be fitted on said flange and soldered thereto.

The provision of the ribs or flanges to the box at its top and bottom ends, affords rigidity thereto and maintains the shape thereof, which is particularly important in respect of the upper end of the box that is closed by the hinged lid 8, since it maintains the shape of the edge and prevents distortion thereof in ordinary usage, so that the lid can, with ease and facility, be opened and closed, the rim of the lid of the box always passing over and neatly fitting the stiffened upper edge of the front and end walls of the box. As shown in Fig. 4 of the drawing the side edges of the rear wall of the box are turned forwardly, as at 10, over or against the rear edges of the end walls of the box and may be soldered thereto.

In those characters of box having one wall concave and the other convex, difficulty exists in closing the lid upon the body of the box, by reason of the fact that but one hinge—and that a very short one, is or can be employed to connect the cover to the box, on which hinge the lid has more or less play, so that when it is attempted to close the same on the body of the box it is almost invariably out of line to have the rim thereof accurately pass over the lid of the box to accomplish the closing. This is a source of great inconvenience.

According to my invention, by reason of the flat wall of the box, the lid may be connected thereto by a plurality of hinges or by a single long hinge co-extensive with the width of the rear wall and corresponding edge of the lid. As shown, two hinges are

utilized, and the hinges are constructed in the following manner. The upper edge of the flat wall of the box is cut away at a plurality of places 11 to expose the pintle 12 of the hinge. The pintle consists of a wire rod which is co-extensive in length with the upper edge of the rear wall and secured in place by folding the upper edge of the wall thereabout as best shown at 13 in Fig. 2 of the drawing. Coincident with the cut-away portions 11 the lid or cover is provided with projecting tongues 14 which are folded about the exposed portions of the pintles, whereby the lid is movably connected to the box body at separate points and there is no looseness or play of the lid or cover whereby it could get out of accurate register with the upper edge of the box body. The flat rear wall is important in respect of the practical hinging of the lid thereto so that it may be easily and accurately opened, and without especial manipulation thereof, be again closed over the mouth of the box.

By my invention I provide a box which can be very easily slipped into and withdrawn from a garment pocket, and when disposed therein, rest comfortably against the body of the person, and which can be conveniently packed in a valise or lunch basket or fishing kit or the like, and one while attaining these useful purposes, presents a maximum interior holding chamber.

Having thus described my invention, what I claim is:

A box having a convex front wall, a flat rear wall and convex end walls merging into said front and rear walls without sharp angles, the rear wall being provided at its upper edge with a plurality of cut away portions, a pintle co-extensive in length with the edge of said rear wall and secured thereto by folding the edge of the latter thereabout, portions of said pintle being exposed in said cut away portions, a cover provided with a plurality of tongues coincident with and folded about said exposed portions of the pintle whereby the lid is hinged to the box at separate points to provide a hinged connection co-extensive with the edge of the rear wall, said cover having a depending flange conforming to the outline of the front and end walls of the body, inwardly turned flanges at the lower edge of the front end and rear walls and a box bottom fitted within the box body against said inwardly turned flange.

In testimony whereof I have hereunto set my hand in presence of two subscribing witnesses.

SAML. W. HELM.
